(57) **CLAIM**

The ornamental design for a “toy stick element,” as shown and described.

DESCRIPTION

FIG. 1 is a perspective view of a toy stick element showing our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof; and,

FIG. 8 is a perspective view thereof, with the toy stick element shown in its environmental use.

The broken lines, which define the bounds of the claimed design form no part thereof.

The broken lines environmental are for illustrative purpose only and form no part of the claimed design.

1 Claim, 5 Drawing Sheets
